UNITED STATES PATENT OFFICE.

SVAN NORDEN, OF CRANSTON, RHODE ISLAND, ASSIGNOR TO S. NORDEN & COMPANY, OF PROVIDENCE, RHODE ISLAND, A PARTNERSHIP CONSISTING OF SVAN NORDEN, OF CRANSTON, RHODE ISLAND, AND HERMAN S. RICH, OF PROVIDENCE, RHODE ISLAND.

MACHINE FOR TIPPING SHOE LACES.

Application filed November 29, 1920. Serial No. 426,935.

To all whom it may concern:

Be it known that I, SVAN NORDEN, a citizen of the United States, residing at Cranston, in the county of Providence, State of 5 Rhode Island, have invented certain new and useful Improvements in Machines for Tipping Shoe Laces, of which the following is a specification.

My invention relates to improvements in 10 tipping-machines for applying metal tips to shoe-laces, corset-laces or the like.

One object of the invention is to provide a machine for rolling or bending a metal blank around the lace and forcing its over-lapping edges together to grip the fabric 15 to secure it thereto.

Another object of the invention is to provide automatically-operating means for holding the lace in position on the blank 20 while the latter is being rolled around it.

Another object of the invention is to provide means for forming a double-length tip from a single blank at one operation of the machine; and for severing the blank at the 25 completion of the tipping operation, whereby to divide it into separate tips for the ends of individual laces.

Further objects of the invention are to simplify the structure of the machine; to 30 render it easy and convenient to operate; and to increase its productive capacity while also providing for improvement in the quality and appearance of its product.

The manner and means for carrying out 35 these improvements are fully set forth in the following specification which describes a preferred embodiment of the invention as illustrated in the accompanying drawings.

In the drawings:

Fig. 1 is a side elevation of a tipping-machine embodying the invention;

Fig. 2, a detail view in reduced scale of the operating lever of the machine;

Fig. 3, a plan view of the main operating 45 parts of the machine showing the tip-forming dies in open position;

Fig. 4, a similar view showing the dies in closed relation;

Fig. 5, a sectional view through the dies 50 taken on the line 5—5 of Fig. 3, looking in the direction indicated by the arrows;

Fig. 6, an enlarged side elevation in detail of the working parts of the dies show-

ing the lace-positioning means in relation thereto at the start of the tip-forming operation;

Fig. 7, a similar view showing the dies in position at the completion of the forming operation and illustrating the lace-holding means released;

Fig. 8, a perspective view of the blank from which the tips are formed; and

Fig. 9, a perspective view of the finished tip affixed to the lace.

My present improved tipping-machine is 65 similar in some respects to that shown and described in my prior U. S. Letters Patent No. 1,348,660, dated August 3, 1920, but has certain important features of distinction as next explained. The machine of the earlier 70 patent is designed to form and affix a single tip to the end of the lace at each operation; whereas, in the present invention the new machine operates to form two connected tips from a single blank and to then sever the 75 formed blank midway of its ends to divide it into two separate tips. In the machine of the patent a single set of dies operates on the opposite edges of the blank to roll it around the lace, while in the present machine I employ two sets of parallel dies operating initially in synchrony on the blank, while one of the sets is also adapted to slide past the other set to effect a shearing action on the formed blank to divide it into two 80 separate tips. Stated briefly, the opposite dies are arranged in pairs, and after all of the several dies have been simultaneously brought into action to form a double-length tip one set of dies moves past the other to 85 cut the tip in two.

Referring to the drawings, my improved machine comprises a base or standard 2 adapted to be set upon a bench or other support 3, and provided with side-lugs 4 through which are inserted screws 5 for fastening it in place. The base 2 is of wedge-shape in side elevation with its upper inclined face adapted to support the dies which operate to form and affix the metal 100 tips to the laces. At its apex end the base 2 is provided with an upstanding abutment or block 6 which is cut away at 7 to form an inclined, recessed seat 8 for one of the fixed dies C. The die C is fastened down 105 to the seat 8 by means of a bolt 10 with its

end abutting the shoulder 7, whereby to brace it against the thrust of the movable die D which cooperates with it.

The movable die D is carried at the end 5 of a slide 12 which is adapted to be reciprocated in a guideway 14 in the upper inclined portion of the standard or base 2. The slide 12 is constructed in the form of a flat bar of rectangular cross-section and is disposed alongside a similar bar or slide 15 10 extending parallel therewith in the guideway 14. The slides 12 and 15 are held in place in the guideway 14 by means of a flat cover-plate 16 secured to the upstanding sides 17 of the guideway 14 by screws 18. It will be noted from Fig. 3 that the slide 15 is somewhat narrower than the slide 12 and beneath it is a third slide or bar 20, which, for convenience of description, I shall 20 term the cutting-off slide. Referring to Figs. 1 and 4, the cutting-off slide 20 is held in a slot or guideway 21 extending the length of the upper inclined face of the base 2. The slot 21 is cut deeper into the rearward 25 part of the base 2 than the guideway 14 and it will be seen from Fig. 3 that the slide 20 is of greater width than that of the overlying slide 15 so that both the slide 12 and the slide 15 rest upon its upper 30 face.

At the lower end of the cutting-off slide 20 is an upstanding block or abutment 22 similar in form to the abutment 6 on the forward end of the base 2. The abutment 22 35 is provided with a recessed seat 23 for the normally fixed die C' which is arranged opposite to and in alinement with its companion die C. The die C' is secured to its seat 23 by means of a bolt 19 and is arranged 40 with its rearward end abutting a shoulder 24 on the abutment 22 to take the thrust against its forward working face. At the opposite end of the bar or slide 20, see Fig. 1, is a depending lug or abutment 25 overhanging 45 the rearward end of the base 2. A stud 26 is screwed through the lug 25 with its end adapted to strike against the rear wall of the base 2 to limit the extent of forward movement of the slide 20 in the direction indicated by the arrow x, Fig. 1. The stud 26 is adjustable to regulate the stroke of the slide 20 and is provided with a check-nut 27 for locking it in position. Surrounding the forward end of the stud 26 is a coil 55 spring 28 which is held under compression between the lug 25 on the slide 20 and a pocket 29 in the base 2. The spring 28 tends to hold the slide 20 in retracted position, a stop-shoulder 30 on the side of the slide, see 60 Fig. 3, being adapted to engage with an opposite shoulder 31 on the base 2 whereby the slide is normally maintained in the position here shown with the fixed die C' at its end in exact register with the opposite or 65 companion die C. Referring to Figs. 3, 4

and 5, the cutting-off slide 20 abuts the side of the block or abutment 6 on the forward end of the base 2 and is held thereagainst by a cleat 32 fastened to the side of the base by screws 33. The cleat 32 is formed with 70 a key or feather 34 extending along its upper edge and fitted to a groove or spline 35 in the side of the slide. In this manner the forward end of the slide 20 is braced and guided in its movement to prevent it 75 from lifting away from the base 2 on which it slides.

The cooperating dies D, D' and C, C' which act to roll the tip-blank around the lace are substantially the same in form as those 80 described in my prior patent before referred to. Furthermore, the two fixed dies C, C' are identical in form, and both movable dies D, D' are of the same structure and arrangement so that it will only be necessary 85 to describe briefly one set of dies. Referring particularly to Figs. 1 and 3, the fixed die C takes the form of a substantially flat rectangular plate which is cut away on its under side at 36 to form the forwardly-90 projecting overhanging extension 38. The forward end of the projecting portion 38 is beveled rearwardly on its under side at 39 with the bevel terminating in a semicircular recess 40 correspond-95 ing to the cylindrical shape of the tip to be formed. The concaved recess 40 thus forms the working-face of the die C, its lower sharp edge serving as a prow to slide in under the edge of the blank to initiate 100 the bending or rolling action thereof. Cut into the top of the overhanging portion 38 of the die C are a plurality of slots 41 formed with inclined bottoms 42, see Figs. 6 and 7, which serve as wedges for a purpose 105 as later explained. As shown in Figs. 3 and 4, the two companion dies C and C' are arranged in closely adjacent relation with their working faces in alinement laterally of the base 2.

Referring particularly to Fig. 1, the movable die D comprises two superimposed members 44 and 45 which are clamped to the forward end of the slide 12 by means of an overlying plate 46. The base-plate 44, which forms the rest for the blank, is set into a recessed seat 47 at the forward end of the slide 12 with its rearward end abutting a shoulder 48. The forward end of the plate or rest 44 projects beyond the slide 12 115 and is reduced in thickness to adapt it to slide in under the overhanging portion 38 of the fixed die C. Resting on the top of the plate 44 is the main die-member 45 which is formed with a rearwardly-beveled upper 120 face 49 adapted to slide in under the undercut beveled face 39 of the fixed die C. At the front of the beveled portion 49 of the die D is an undercut circular face 50 which is complementary to the semicircular recess 40 125 130

in the die C. The lower edge 51 of the face 50 overhangs a curved shoulder or ledge 52 extending transversely of the base-plate 44 whereby to serve as an abutment to overlie 5 the edge of the blank B, see Fig. 6, when the main die-element 45 is in its forward position as here shown. The element 45 is slideable on the plate 44 to withdrawn its edge 51 from this position whereby, when the 10 die D comes into cooperation with the die C, the several faces 50, 52 and 40 will be combined to form a complete circle as shown in Fig. 7.

Referring now to Fig. 4, the die-member 15 45 is cut through with a rectangular opening at its center to provide two opposite parallel legs 55 which straddle the sides of a raised block or abutment 56 on the top of the base-plate 44. The forward edge of the block 56 20 abuts the end of the opening in the member 45 to limit the rearward sliding movement of the latter whereby to serve as a stop when the working faces 50 and 52 are brought into register. The member 45 is slid forward on 25 the plate 44 by its contact with the edge of the cover-plate 16 under the action of the rearward motion of the supporting slide 12. That is to say, as the slide 12 moves back 30 in the direction opposite to that indicated by the arrow x , Fig. 1, the ends of the legs 55 of the member 45 strike against a projecting strip or fin 57 on the edge of the cover-plate 16 to cause the member to be pushed slightly forward with its edge 51 overhanging the 35 ledge 52 on the plate 44.

As before stated, the die-member 45 is held down against the base-plate 44 by means of the top-plate 46 which is fastened to the top of the block 56 by screws 58, see 40 Figs. 1, 3 and 4. The complete die D is secured to its support or slide 12 by means of a bolt 59 passing down through the block 56 on the base-plate 44, see Figs. 3 and 4. The top-plate 46 projects beyond the forward end of the die-member 45 and is slotted 45 to receive a pair of narrow fingers or levers 60. The levers 60 are pivoted within the slots on a cross-pin 61 driven through the side of the plate, see Fig. 1. The levers 60 50 are formed with arms 62 resting on the top of the plate 46 and normally held thereagainst by the legs 63 of a wire spring 64. The spring 64 is formed with a central loop 55 fastened to the top of the plate 46 by a screw 66. From the central loop the wire extends in two opposite coils 67 which continue in the legs 63, the latter being bent at right angles at their outer ends to overlie the edges of the levers 60. At the outer ends of 60 the levers 60 are fingers 68 which project downwardly into proximity with the top of the blank-rest 44. The fingers 68 are adapted to engage the edge of the lace L placed on top of the blank B, and serve to push 65 the lace over into position to be rolled into

the tip, see Fig. 6. As the dies D and C close together the fingers 68 slide into the inclined slots 41 of the die C to rock the levers out of the way, as shown in Fig. 7.

The reciprocating slides 12 and 15 carrying the movable dies D and C are actuated from a rockable lever 70 which, as shown in Fig. 1, is pivoted on a rod or shaft 71 extending through the sides of the base 2 and held in place by cotter-pins 72. 75 The lever 70 may be connected to be oscillated from suitable power-driven means if desired or, in accordance with the usual method, is operated manually. For this purpose a foot-rest or treadle comprising a 80 cross-bar or rod 73 projects from its sides at the lower end as shown in the detail view, Fig. 2. The upper end of the lever 70 is of inverted hammer-shape terminating in an enlargement 74 which is rounded off on the 85 sides, see Fig. 3. Pivoted on the shaft 71 at the side of the lever 70 is an auxiliary lever 75 having its upper end 76 shaped to the same contour and adapted to be held in alinement therewith. The auxiliary lever 90 75 has its lower arm extending forwardly at an angle to the main lever 70 and near its end is a pin 77 engaging a slot 78 in a projecting cross-piece 79. The cross-piece 79 is riveted or otherwise fastened to the side 95 of the lever 70 and its slot 78 serves as a guide and stop to control the rocking movement of the lever 75 with respect to the lever 70. A coil-spring 80 of heavy wire is attached at one end to a pin 81 at the lower 100 end of the lever 75 and is anchored at its opposite end to a pin 82 on the side of the lever 70. The spring 80 acts to hold the auxiliary lever 75 in the position illustrated in Fig. 2 with its upper end or head 76 in 105 register with the head 74 of the lever 70.

Referring now to Figs. 1 and 3, the hammer-like ends of both levers 70 and 75 project upwardly within the walls of the base 2 with their enlarged heads 74 and 76 engaging respectively with the ends of two opposite slots 84 and 86 cut into the adjacent sides of the slides 15 and 12. The head 74 on the main lever 70 is thus engaged with the slide 15 to slide the latter from the rocking motion of the lever; while the head 76 of the auxiliary lever 75 likewise acts on the slide 12 when both levers move together. It will be noted from Fig. 1 that the lower cutting-off slide 20 is cut away on its side 110 at 88 to provide clearance for both of the levers 70 and 75 so that neither of them engages with it. The coaction of these parts will be further described in connection with the operation of the complete machine as next explained.

Referring to Figs. 1 and 3, these views illustrate the machine with the dies open ready to receive the blank B from which the tip is to be formed. Fig. 8 shows the 115 120 125 130

blank B as consisting in a substantially flat strip of sheet-metal having its edges bent or curled upwardly to form the upstanding marginal ribs or flanges b. At either end 5 the blank B is punched with a series of perforations forming sharp-edged projections or prongs b' on its upper face adapted to bite into the fabric of the lace to grip its end to prevent the tip from pulling off.

10 With the parts of the machine in the position illustrated in Fig. 1 the operator places the tip-blank B on the rest or base-plate 44 and lays the lacing strip L across it. It will be noted that with the slides 12 15 and 15 retracted to the rearward limit of their throw, as shown in Fig. 1, the die-member 45 will be engaged by the fin 57 on the cover-plate 16 so that its forward lower edge 51 is projected beyond the ledge 52 on the rest 44. The operator places his foot 20 on the cross-arm 73 of the operating lever 70 and pushes the lever back to rock its upper end forward. As the head 74 of the lever 70 is moved forward its auxiliary lever 75 is carried with it due to its connection therewith by the spring 80. The heads 74 and 76 of the levers 70 and 75 are thus caused to act in unison against the ends of the slides 15 and 12 25 to push the slides forward in the direction indicated by the arrow x, Fig. 1. The two slides 12 and 15 move forward together carrying the dies D, D' with them and the ends of the adjacent plates 44 on which the blank B rests will be slid in under the projecting ends of the fixed dies C, C'. The initial movement of the dies D, D' will carry the blank B forward until its edge comes against the working faces 40 of the 30 fixed dies C, C'; and as the dies D, D' continue to move forward the rearward edge of the blank will be engaged by the ledge or shoulder 52 on the rests 44 with the overhanging edge portion 51 of the members 45 overlapping its upturned flange, b, see Fig. 6. During this forward movement of the dies D, D' the levers 60 will ride across the edge of the blank B, and engaging with the side of the lace L will push the latter 35 bodily toward the fixed dies C, C'. Now, as the movement of the dies D, D' is continued still further their pressure on the rearward edge of the blank B will cause the sharp prong of the fixed dies C, C' to pry up its forward edge and cause it to be rolled around the recess in the face of the fixed dies C, C' in the manner illustrated in Fig. 6. Meanwhile, the levers 60 on the movable dies D, D' urge the lace L forward 40 and force it into the curled-over edge of the blank B. This action is continued until the lace L is rolled completely into the blank and enclosed by its sides, and eventually as the dies close together, as shown in 45 Fig. 7, the blank is compressed between the

working faces 40 and 50 and its edges clenched together to form a double-length tip. As the dies D, D' close against the dies C, C' the levers 60 ride into the inclined slots 41 and are tilted upwardly against the action of their springs 64 to remove the lace-holding fingers 68 out of the way.

It has before been noted that the tip-blank B is of double the length of the completed lacing-tip T, see Figs. 8 and 9, and hence each blank as it is rolled around the lacing forms two connected tips. To provide the two separate tips the forward blank must therefore be cut apart and the operation of severing the blank at its center is 50 performed as next explained: As the dies D and D' are brought into register with the dies C and C' the die D will be prevented from further movement by the engagement of the forward end of the plate 55 or rest 44 with the end of the undercut portion 36 of the fixed die C. That is to say, the die C being fast on the base 2 serves as a stop to limit the movement of the die D. As regards the opposite die C, however, 60 this is mounted on the lower end of the slide 20 and consequently may be caused to move therewith after the die D' comes against its forward edge.

It has before been explained that the slide 65 20 is held in retracted position by the spring 28 bearing against the end wall of the base 2. The spring 28 is constructed of heavy wire so that it exerts sufficient pressure on the slide 20 to resist the first thrust of the die D' 70 against the die C'. That is to say, the spring 28 holds the slide 20 with the die C' in alignment with its companion die C until the dies D, D' have completed the forming of the blank as shown in Fig. 7. After the 75 blank has been clenched around the lacing, however, the continued pressure of the operator's foot on the lever 70 will cause the latter to slide the slide 15 to move the die D' beyond the die D. This action is actually 80 effected at one continuous stroke of the lever 70, its first movement bringing the dies together, while at the end of its stroke the slide 15 is moved still further to slide the dies D' and C' past the dies D and C. It 85 will be noted from Figs. 3 and 4 that the slide 15 for the die D' is operated from the head 74 of the lever 70; while the slide 12 which carries the die D is operated from the head 76 of the auxiliary lever 75. The lever 90 75 is operated from the main lever 70 through its connection therewith by the spring 80 and hence as the slide 12 comes to rest with the die D against the fixed die C the lever 70 is allowed to move past the lever 75 to 95 continue the motion of the slide 15.

As the movement of the slide 15 is continued, as indicated by the dotted lines in Fig. 4, the dies D' and C' slide past the dies D and C and their adjacent faces act in the 100

manner of shears to sever the formed blank at its center to divide it into two separate tips. As the metal strip is thus cut in two the sharp edges of its severed portions act to shear the fabric lace at the same point. Stated briefly, the rolled over blank is severed in twain and the lace sheared off flush with the ends of the completed tips thus formed.

10 It has been explained that the shearing stroke of the die D is provided for by the movement of the slide 20 against the tension of the spring 28 and the extent of this motion is limited by the engagement of the 15 stop-screw 26 with the rearward wall of the base 2. After the cutting-off stroke has been completed the foot-lever 70 is released to allow its lower end to swing forward. This latter movement of the lever 70 may be effected through the action of gravity or a 20 suitable spring, not herein shown, may be employed for the purpose. Upon the release of the lever 70 the cutting-off slide 20 will be slid back by its spring 28 until its 25 stop-shoulder 30 engages the opposite shoulder 31 on the base 2, at which juncture the die C' will be brought into alignment with its companion die C. The further return of the lever 70 causes its head 74 to come into 30 alignment with the head 76 on the auxiliary lever 75, see Fig. 2, and as the pin 77 on the lever 75 reaches the end of the slot 78 in the cross-piece 79 both levers will be carried back together to return the slides 12 and 15 35 to first position. As the slides 12 and 15 are thus retracted to withdraw the dies D and D' from the dies C, C' the completed tips are released therefrom and may be removed from the machine. As the slides 12 and 15 40 reach the end of their rearward stroke the edge of the die-member 45 strikes against the fin 57 on the fixed cover-plate 16, see Fig. 1, to project the member forward to overhang the shoulder 52 to set it in operative 45 position to receive a new blank placed upon the rest 44. As the dies D, D' move back from the dies C, C' the lace-holding levers 60 ride out from the slots 41 and are returned to operative position as shown in 50 Fig. 1. In this way the rearward stroke of the lever 70 returns all of the parts to operative position for acting on a fresh blank applied to the machine.

It will be seen that the machine is entirely 55 automatic in action and may be operated continuously to produce the finished tips at a fast rate. Furthermore, the machine forms and affixes two complete tips at each operation, thus doubling the production of the 60 ordinary type of machine. The duplex form of blank also tends to produce a better formed and more symmetrical tip with greater uniformity in the product. The strip of lacing is severed accurately at the 65 proper point with its ends cut off smooth

and flush with the ends of the tips so that there are no loose threads or ragged ends. In general the machine produces an improved product at an increased rate of production, and with a minimum of care and 70 attention on the part of the operator.

Various modifications may be made in the structure and arrangement of the parts of the machine without departing from the spirit or scope of the invention; therefore, 75 without limiting myself to the exact embodiment herein shown and described, I claim:

1. In a tipping machine, the combination of two sets of dies adapted to operate on a blank to apply a double-length tip to the 80 lace, one set of dies being displaceable in relation to the other set to shear the double tip in twain, a lever for operating the two sets of dies in unison, and means connecting the lever to said dies to adapt it to move 85 one set of dies past the other set to effect the shearing action therebetween.

2. In a tipping machine, the combination of two sets of dies adapted to operate on a blank to apply a double-length tip to the 90 lace, one set of dies being displaceable in relation to the other set to shear the double tip in twain, a two part lever for operating the two sets of dies in unison, and means for adapting one part of the lever to yield 95 whereby the other part will move one set of dies past the other set to effect the shearing action therebetween.

3. In a tipping machine, the combination of two sets of dies adapted to operate on a 100 blank to apply a double-length tip to the lace, one set of dies being displaceable in relation to the other set to shear the double tip in twain, a main lever for operating the dies, and a second auxiliary lever connected to the main lever and adapted to yield in 105 relation thereto to allow one set of dies to be carried past the other set to effect the shearing action therebetween.

4. In a tipping machine, the combination 110 with a base, of a die fixed on the base, a slide slidable on the base, a die on the slide arranged opposite the fixed die, means for holding said slide in position with its die in alignment with the fixed die, a pair of 115 slides adapted for movement independently of the first slide, a pair of dies carried by said last-named slides, and means to move the pair of slides in unison and to continue the movement of one of them to slide the 120 first-named slide.

5. In a tipping machine, the combination with a base, of a die fixed on the base, a slide slidable on the base, a die carried by the slide, a spring for holding the slide in 125 position with its die in alignment with the fixed die, a pair of slides slidable on the base independently of the first slide, a pair of dies carried by the last-named slides, and a compound lever for sliding the pair of 130

slides while moving one of them past the other to slide the first-named slide.

6. In a tipping machine, the combination of opposite cooperating dies adapted to act on a blank to form it into a tip enclosing the lace, a lever pivoted on one die, a spring acting on the lever to normally maintain it

in position to engage the lace to hold it in place as the blank is bent around it, and means on the other die for tilting the lever 10 out of the way as the dies come together.

In testimony whereof I affix my signature.

SVAN NORDEN.
